FUEL DISTRIBUTING SYSTEM

Andrew M. Hunt, deceased, late of Berkeley, Calif.,
by Crocker First Federal Trust Company, San
Francisco, Calif., executor, assignee to The
Standard Stoker Company, Incorporated, a cor-
poration of Delaware

Application September 25, 1931, Serial No. 565,051

6 Claims. (Cl. 110—101)

This invention relates to stokers of the scatter feed type wherein fuel is discharged over a firebed by a pressure fluid blast and has for its object the provision of a new and improved fuel distributing system and more particularly to a new and improved firing table for separating the fine from the coarse fuel and separately distributing each over the firebed.

The present invention provides an improved system of distributing fuel wherein the coarse and fine fuel are separated and each is separately discharged over the firebed by blasts of different intensities which may be controlled and regulated to meet the varying conditions of firing.

15 Numerous attempts have heretofore been made to separate coarse and fine fuel with various degrees of success or failure. The present invention contemplates the use of an improved firing table in the form of a hollow casting, the 20 top wall of which is provided with a riddle permitting fine fuel to drop therethrough and coarse fuel to pass thereover, and the bottom wall of which is provided with means for evacuating the hollow firing table thereby drawing fine fuel 25 through the riddle and effecting a complete separation from the coarse fuel, and discharging the fine fuel through openings provided in the front wall of the firing table.

The invention further consists in the parts 30 and the arrangement of the parts as will be hereinafter described and as illustrated in the accompanying drawing, in which

Fig. 1 is a vertical section of a portion of a furnace and a stoker therefor, showing the invention in position therein;

Fig. 2 is a detail plan section on the line 2—2 of Fig. 1;

Fig. 3 is an end view of the stoker and firing table taken through the firing opening from 40 within the firebox; and

Fig. 4 is a section on the line 4—4 of Fig. 2.

The invention is illustrated and described as applied to a locomotive, but it will be apparent that the invention is equally applicable to furnaces of other types wherein the invention may 45 be used to advantage.

A portion of a locomotive boiler firebox is shown at 10 and is provided with the backwall 11 having a firing opening 12 therethrough. The 50 firebox grates are shown at 13.

The invention is applicable to various types of stokers and only so much of the stoker as is necessary to an understanding of the invention has been illustrated. The portion of the stoker 55 shown comprises a riser conduit 14 rigidly supported from the backwall 11 by a bracket 15. A conveyor screw 16 advances the fuel through the riser 14 to the firing opening where it is received on a firing table 17 which will be described in detail further on in the description.

The riser conduit 14 is provided with a removable cover section 18, which may be hinged at its upper end providing access to the interior of the riser conduit.

The fuel delivered by the riser conduit 14 is 65 received on the firing table 17 from whence it is projected into the firebox. The firing table 17 is preferably, but not necessarily, in the form of an integral casting provided with the fine fuel chamber 19 and comprising top and bottom 70 walls 20 and 21 respectively, and front and rear walls 22 and 23 respectively. The firing table 17 is securely fastened to the depending flange 24 of the forward wall of the riser conduit 14 through its rear wall 23 by suitable means, as by 75 the bolts 25.

The rearward portion 26 of the top wall 20 is offset in a slightly higher plane from the forward portion 27 of the top wall 20. A steam chamber 28 is formed in the top wall 20 at the 80 offset between the forward and rearward portions of the top wall 20. The rearward portion 26 of the firing table top wall 20 is apertured forming a riddle 29 for separating the fine fuel from the coarse fuel. The coarse fuel is urged 85 forwardly across the rearward portion 26 of the firing table top wall 20 by the impelling action of the screw 16 onto the forward portion 27 from where it is distributed over the fire by a pressure fluid blast issuing from the chamber 28 through 90 the jet openings 30. The forward side portions of the forward portion 27 of the firing table 20 are provided with the pockets 31, which serve to receive and direct a portion of the coarse fuel to the rear corners of the firebox.

The front wall 22 of the firing table 17 is provided with a plurality of fine fuel discharge openings 32, which are preferably slightly larger in diameter at the outside than at the inside in order to make them self clearing. A steam chamber 33 is formed in the bottom wall 21 intermediate the front and rear walls of the firing table 27. The forward face of the steam chamber 33 is provided with a plurality of jet openings 34 in alignment with the openings 32, whereby a blast of pressure fluid is discharged from the chamber 33 through the jet openings 34 and the fuel discharge openings 32 creating a vacuum inside the firing table 27 drawing the fine fuel through the riddle 29 and discharging it through the openings 32 over the fire beneath the path of the coarse fuel.

Preferably, the blast issuing from the jet openings 30 of the top wall of the firing table is more powerful than the lower blast issuing from the jet openings 34, this arrangement being desirable because the high pressure blast distributes the lump fuel, whereas, the lower blast scatters the finer particles of fuel which do not require the same force for distribution over the fire. The 115 120

upper blast also serves as a cover or blanket for the lower blast, preventing to a considerable extent the loss of fine fuel normally discharged through the stack unconsumed because of the 5 heavy draft during operation of the locomotive.

The chamber 28 receives pressure fluid from a suitable source of supply through the supply pipes 35 and the chamber 33 receives pressure fluid through the supply pipe 36.

10 What is claimed is:

1. In a fuel distributing system for scattering fuel in aerial paths over a fire, a chambered firing table having top, bottom and front walls, means for delivering fuel to said top wall, riddling means 15 in the rearward portion of said top wall whereby fine fuel drops through said riddling means onto said bottom wall and coarse fuel passes thereover, pressure fluid blast means forward of said riddling means for projecting the coarse fuel forwardly across the forward portion of said top wall, fine fuel discharge openings in the front wall of said chambered firing table, and means arranged to evacuate said chambered firing table entraining fine fuel laden air through 20 said riddle and discharging it across said bottom wall and through said fine fuel discharge openings.

2. In a fuel distributing system for scattering fuel in aerial paths over a fire, an approximately 30 rectangular hollow firing table including a top, bottom and front wall, means for delivering fuel to the top wall of said firing table, riddling means in the rearward portion of said top wall whereby fine fuel drops through said riddling means onto said bottom wall and coarse fuel passes thereover, pressure fluid blast means in said top wall forward of said riddling means for distributing the coarse fuel, a plurality of openings in the front wall of said hollow firing table a pressure fluid 35 blast means in said bottom wall arranged to issue through said openings in the front wall of said firing table creating a suction entraining fine fuel laden air through said riddling means and discharging it through the openings in said firing table front wall.

3. In a fuel distributing system for scattering fuel in aerial paths over a fire, a cored firing table comprising a top wall having a pressure fluid chamber formed therein intermediate its 40 forward and rearward edges, a bottom wall having a pressure fluid chamber formed therein and a front wall, means for delivering fuel to the top wall of said firing table, perforations in the rearward portion of said top wall forming riddling means whereby fine fuel drops through said riddling means onto said bottom wall and coarse fuel passes thereover, fine fuel discharge openings in the front wall of said firing table, a series of 45 forwardly directed jets communicating with the pressure fluid chamber in said top wall for distributing coarse fuel and a series of forwardly directed jets communicating with the pressure fluid chamber in said bottom wall arranged to evacuate the cored portion of said firing table entraining fine fuel laden air through said riddling means and discharging it through the openings in said firing table front wall.

4. In a fuel distributing system for scattering fuel in aerial paths over a fire, a cored firing table comprising a top wall having a pressure fluid chamber formed therein intermediate its forward and rearward edges, a bottom wall having a pres-

sure fluid chamber formed therein intermediate its forward and rearward edges and a front wall, said pressure fluid chambers and those portions of the top and bottom walls rearward thereof being raised with respect to the forward portions 80 of said top and bottom walls respectively, the rearward portion of said top wall being formed as a riddle for separating fine fuel from coarse fuel, the fine fuel dropping through said riddle onto said bottom wall and coarse fuel passing over said riddle, a series of jets communicating with the pressure fluid chamber in said top wall for issuing a blast across the forward portion of said top wall for distributing the coarse fuel, pockets 85 formed in the forward side portions of said top wall for deflecting a portion of the coarse fuel laterally, a series of openings in the front wall of said firing table, a series of jets communicating with the pressure fluid chamber in said bottom wall for issuing a blast across the forward portion 90 of said bottom wall through said openings in said front wall whereby suction is created in said cored portion of said firing table entraining fine fuel laden air through said riddle and projecting it forwardly across the forward portion 95 of said bottom wall.

5. As a new article of manufacture a firing table in the form of a unitary member comprising top, bottom, front, rear and sidewalls enclosing a cavity, pressure fluid chambers formed in 100 said top and said bottom walls, respectively, intermediate said front and rear walls, openings in the front wall of said firing table communicating with said cavity, a series of jets communicating with the pressure fluid chamber in said top 105 wall and directed across the forward portion of said top wall, a series of jets communicating with the pressure fluid chamber in said bottom wall and directed across the forward portion of said bottom wall and a plurality of perforations in the 110 rear portion of said firing table top wall forming a riddle, said riddle being spaced apart from the bottom wall of said firing table.

6. As a new article of manufacture a firing table in the form of a unitary member comprising 115 top, bottom, rear, front and sidewalls enclosing a cavity, pressure fluid chambers formed in said top wall and said bottom wall respectively intermediate said front and rear walls, said pressure fluid chambers and the rearward portion of 120 said top and bottom walls being raised with respect to the forward portion of said top and bottom walls respectively, a plurality of perforations in the rearward portion of said top wall forming a riddle, said riddle being spaced apart from the bottom wall of said firing table, a series 125 of jets communicating with the pressure fluid chamber in said top wall directed across the forward portion of said top wall, a series of jets communicating with the pressure fluid chamber 130 in said bottom wall and directed across the forward portion of said bottom wall and a plurality of openings in the lower portion of the firing table front wall in alignment with the jets in said bottom wall pressure fluid chamber.
